UNITED STATES PATENT OFFICE.

CLARANCE W. THOMPSON AND WILLIAM J. QUIGLEY, OF WILMINGTON, DELAWARE,
ASSIGNORS TO RIVERVIEW CEMETERY COMPANY, OF WILMINGTON, DELAWARE,
A CORPORATION OF DELAWARE.

BURIAL VAULT.

1,427,243.

Specification of Letters Patent. Patented Aug. 29, 1922.

Application filed August 15, 1921. Serial No. 492,614.

To all whom it may concern:

Be it known that we, CLARANCE W. THOMPSON and WILLIAM J. QUIGLEY, citizens of the United States, residing at Wilmington, in the county of New Castle and State of Delaware, have invented certain new and useful Improvements in Burial Vaults, of which the following is a specification.

10 This invention relates to vaults of the type that are adapted to be placed in the ground to contain coffins holding dead bodies, and it is adapted particularly to vaults formed of concrete or other initially 15 plastic material.

It is an object of the invention so to form the joint between the lower or container portion of the vault and its cover that a seal will be afforded between abutting parts that 20 will be reliable in preventing seepage of moisture into the vault.

Another object of the invention is to form the vault so that the weight of the cover and of the earth thereabove will be imposed 25 directly on the wall of the lower portion in lines coincident with those of the walls.

When considered in connection with the description herein, the characteristics of the invention will be apparent from the accompanying drawing, forming part hereof, wherein an embodiment of the invention, as embodied in a concrete vault, is disclosed, for purposes of illustration.

Like reference-characters refer to corresponding parts in the views of the drawing, of which—

Fig. 1 is a side elevation;

Fig. 2 is a transverse section; and

Fig. 3 is an enlarged section at the joint.

40 Having more particular reference to the drawing, A designates the substantially rectangular lower or container portion of the vault and B the cover thereof, the cover being of arch shape to afford a structure sufficiently strong to sustain the weight of covering earth thereabove. When those parts are formed of concrete or similar initially plastic material, they preferably are strengthened by reinforcing elements C.

50 The container includes a bottom 4 and a wall 5, which is substantially perpendicular to the bottom and constitutes the sides and ends of the container.

The upper or free edge of the wall 5 is formed with a substantially V-shaped groove 6, which extends entirely and continuously around the container. The outer side of the wall immediately below the outer edge of the groove is disposed in a plane that declines outwardly from the axis of the wall, 60 as shown at 7. This outer face 7 extends from the outer edge of the groove 6 to the top surface 8 of an abutment 9 that projects outwardly from and is formed integrally with the wall and is disposed entirely 65 around the container below the upper edge thereof. The top surface 8 lies in a plane that is substantially perpendicular to the axis of the wall.

The lower or marginal portion of the 70 cover is shaped adjacent to the inner side to afford a tenon-like protuberance or rib 10 arranged to be received by the groove 6 and with surfaces that lie substantially parallel to those of the groove when the cover is in 75 place.

Outside of the protuberance the material of the cover extends downwardly as a flange 11, the lower edge 12 of which lies in a plane substantially parallel to the top surface 8 of the abutment. The inner side 13 of the flange is disposed in a plane that is non-parallel with respect to the outer side 7 of the wall and that is a greater distance from that side at the bottom than at the edge of the groove 6. The parts and abutting surfaces are proportioned in such manner that the abutment 9 extends outside of the flange to hold sealing material.

Although the vault provided by this invention is intended especially to hold a coffin containing a body interred in a grave, it also is adapted for similar use in a mausoleum or the like.

When used in a grave, the container portion A first is lowered thereinto, sealing material 14, such as cement, is placed in the groove 6, against the outer face 7, and on top of the abutment, the coffin thereafter is lowered into the container, and then the cover is lowered into association with the container. When the marginal surfaces of the cover come into abutment with those of the container, the sealing material will be pressed and distributed evenly therebetween. 100 If the sealing material, when first placed

against the surface 7, does not adhere uniformly thereto and remain distributed thereover, it will be wedged to that condition by the non-parallel inner side 13 of the flange 5 11 as the cover becomes seated. Thereafter, the sealing material that may have been pressed outside of the flange and the additional sealing material it may be necessary to add thereto are pointed up, as shown at 15, 10 to provide an outer seal on the projecting portion of the abutment with a pitched outer surface arranged to shed water from the abutment.

It will be seen that the joint between the 15 container and its cover is sealed at four places—in the groove 6, between the abutting sides of the wall and flange, between the lower end of the flange and the upper surface of the abutment, and on the abutment 20 outside of the flange—and that seepage of moisture through the joint thus will be prevented. Moreover, as the flange extends downwardly from the upper edge of the wall at the groove, an additional factor exists to prevent seepage of water, which has a 25 tendency to go downwardly rather than upwardly.

The parts are arranged and proportioned in such manner that the downward effort of 30 the cover is sustained at the top edge of the container-wall where the groove 6 is located, and that effort is directed in lines substantially coincident with those of the wall. Thus the wall is not subjected to the torsional strains that would result from imposition of all or the greater part of the weight 35 sustained by the cover on a projecting abutment, and the wall, accordingly, is not liable to have its integrity impaired by pressure of 40 the cover. In view of this feature, earth may be tamped down forcibly and compactly above the cover while the grave is being filled, and the structure is capable of 45 sustaining the weight of earth required to fill even an unusually deep grave.

The cover is equipped with handles 16 for use in carrying it and in lowering it onto the container.

Having thus described our invention, what we claim as new, and desire to secure by Letters Patent, is—

1. A vault comprising a bottom, a wall substantially perpendicular thereto having a groove in its upper edge and having an outer surface declining outwardly immediately below said groove, an abutment on the outside of said wall below said groove, and a cover having a protuberance arranged to be received by said groove and a depending flange arranged to abut said abutment at its end and to abut said outer surface on its inner side, said inner side of the flange being at a greater distance from said outer surface in its lower than in its upper portion. 55

2. A vault comprising the combination of a container formed with an upright surrounding wall having a V-shaped groove in its upper edge and having an outer face declining immediately below and outwardly 60 from said groove, an abutment on the outside of said wall below said face having an upper surface substantially perpendicular to said wall, and a cover having a protuberance of substantially the same shape as and arranged to be received by said groove and a depending flange arranged to abut said abutment at its end and to abut said outer face on its inner side, said inner side of said flange being a greater distance from said outer face in its lower than in its upper portion 65 whereby sealing material is wedged therebetween, and said abutment extending outside of said flange for the purpose of retaining sealing material. 70

In witness whereof, we affix our signatures.

CLARANCE W. THOMPSON.
WILLIAM J. QUIGLEY.
